UNITED STATES PATENT OFFICE.

GEORGE F. PALDANI, OF WAUKEGAN, ILLINOIS, ASSIGNOR TO PFANSTIEHL COMPANY, INC., OF NORTH CHICAGO, ILLINOIS, A CORPORATION OF NEW YORK.

IGNITION MECHANISM FOR INTERNAL-COMBUSTION ENGINES.

1,299,770.

Specification of Letters Patent. Patented Apr. 8, 1919.

Application filed July 20, 1917. Serial No. 181,675.

To all whom it may concern:

Be it known that I, GEORGE F. PALDANI, a citizen of the United States, residing at Waukegan, in the county of Lake and State 5 of Illinois, have invented a certain new and useful Improvement in Ignition Mechanism for Internal-Combustion Engines, of which the following is a full, clear, concise, and exact description, reference being had to the 10 accompanying drawings, forming a part of this specification.

My invention relates to ignition mechanism for internal combustion engines, and more specifically to interrupter mechanism 15 commonly employed in connection with spark plug ignition systems for automobile engines.

One of the objects of the present invention is the provision of an interrupter contained within a housing which is readily accessible for repairs, simple in construction, and which can be manufactured economically.

A further object of the present invention 25 is the provision of an improved interrupter or contact mechanism which functions to interrupt an electric circuit forming part of the ignition system. One of the novel features of the interrupter mechanism of my invention resides in means whereby the mechanism is rendered inoperative or incapable of controlling its electric circuit when the engine with which it is associated 30 is rotated in a backward direction. It frequently happens in starting the engine that the engine back-fires and thus causes rotation of its crank shaft in a backward direction. The interrupter mechanism of my invention is arranged so that if the crank 35 shaft is rotated in the wrong direction its contacts will be held open and thus prevent sparking within the engine cylinders.

A further object of the present invention is the provision of novel constructions, arrangements, and combinations which go to 45 make a generally more efficient device of this character than has been employed in the past, all of which will be pointed out in detail in connection with the accompanying 50 drawings wherein,

Figure 1 is a side elevational view of the device of my invention, some of the parts being broken away to reveal more clearly the internal construction;

Fig. 2 is an enlarged top view of Fig. 1,

the housing or cover piece being removed, and

Fig. 3 is a bottom view of Fig. 1.

Similar characters of reference refer to similar parts throughout the several views. 60

The device of my invention comprises a base plate 4 and a cover piece or housing 5 removably attached to the base plate 4 in a manner to be pointed out hereinafter. The base 4 is provided with a downwardly extending collar 6 through which the operating shaft 7 of the ignition mechanism extends. Attached to the shaft 7 on the upper side of the base plate 4 is a cam 8 carrying the several cam pieces shown at 70 9-9. If desired the cam 8 may be made a part of the shaft 7. The extreme upper end of the shaft 7 is slotted as shown at 10 and is attached to a revolving distributing arm member 11, the slot 10 of the shaft being 75 arranged to receive a corresponding tongue carried by the distributing arm member so that locking of the distributing arm and shaft is assured. The outer end of the distributing arm 11 carries a conductor piece 80 12 connected to a flat spring 13 engaging a contact 14 located on the axis of the shaft 7 and adapted to be connected to a conductor passed through the knurled extension shown at 15. Carried by the housing 5, which is 85 made of any suitable electrical insulating material, are a plurality of contacts 16 each of which is connected through a conductor, one of which is shown at 17, to a spark plug located in the engine cylinder. As the shaft 90 7 revolves the conductor plate 12 of the distributing arm 11 is arranged to provide an electric circuit through each one of the contacts 16 one after another. The contact piece 12 is arranged so that there is a space 95 of about 20/1000 of an inch between it and one of the adjacent contacts 16 when the distributing arm lies in a position to produce a circuit through one of the contacts.

Carried by the base plate 4 and extending 100 downwardly therefrom is a pin 18 on which is pivotally mounted a lever 19 held in place on the pivot pin by the split washer 20. The end of the lever 19 opposite its pivot is curved inwardly, as shown at 21, and has 105 attached thereto a flat spring 22 extending rearwardly and attached at 23 to the base plate 4. The tendency of the flat spring 22 is to rotate the lever 19 in a counter-clockwise direction (Fig. 2). Reciprocably 110

22

mounted within the lever 19 is a plunger 24 having a restricted portion 25 extending through an aperture provided in the end plate shown at 26. The outer end of the 5 restricted portion 25 carries a head 27 arranged to rest against the plate 26. Extending around the restricted portion 25 of the plunger and interposed between the enlarged lefthand end of the plunger and the 10 plate 26 is a coiled compression spring 28 which normally tends to move the plunger to the left in this figure, the movement to the left being restricted by the head 27. Carried by the lever 19 is a contact 29 ar- 15 ranged to coöperate with a second contact 30 mounted on a flat spring 31 attached at 32 to a plate 33 in turn connected at 34 and 35 to the base plate 4. The end of the spring 31 opposite its support 32 is arranged to 20 engage a lug 36 extending upwardly from the plate 33. The spring 31 is arranged so that it tends to move in a counter-clockwise direction (Fig. 2) and is thereby held in engagement with the lug 36.

25 The mechanism just described forms the interrupter mechanism and its operation is as follows:

The shaft 7 is rotated in the direction indicated by the arrow in Fig. 2 causing the 30 cam pieces 9—9 to engage the underside of the plunger 24 and to oscillate the lever 19 about its pivot 18. As the lever 19 is moved outwardly away from the shaft 7 its contact 29 engages the contact 30 and thereby 35 closes an electric circuit of which the contacts 29 and 30 form a part. As one of the cam pieces 9 recedes from the plunger 24 the lever 19 returns to its original position due to the action of the flat spring 22. It will 40 be observed that the contact mechanism is arranged so that upon closing of the contacts 29 and 30 a certain wiping effect is secured, thus assuring a good electrical connection. If for any reason the shaft 7 is 45 rotated in a direction reverse from that shown by the arrow, as when the engine backfires, the plunger 24 is moved within the lever 19, but the lever is held against movement about its pivot 18 by the spring 22.

50 The closing of the contacts 29 and 30 is thereby prevented when the operating shaft 7 is rotated in a backward direction.

To provide adjustment of the lever 19 its outer end is arranged to engage an eccentric 55 37, preferably constructed of fiber and held in place by a screw 38. In adjusting the contact 29 toward or away from the contact 30 the screw 38 is loosened and the eccentric fiber member 37 rotated to the de- 60 sired position. The screw 38 is then tightened to hold the eccentric in place.

The entire base plate 4 is arranged for oscillation about the shaft 7 and for the purpose of facilitating such oscillation the base plate carries an outwardly extending 65 arm 39 provided with an aperture 40 ar- 70 ranged to receive a link extending from some point convenient to the operator. Ex- 75 tending downwardly from the base plate 4 is a boss 41 to which is attached at 42 a semi- circular flat spring 43 fitting into a pair of 80 guide pieces 44 and 45, also extending down- 85 wardly from the base plate 4. The housing 5 carries the two steel inserts or pins 46 and 47 which extend downwardly through the 90 apertures 48 and 49 provided in the base plate 4. The lower ends of the inserts or pins 46 and 47 are enlarged, as shown at 50 and 51, and extend over the outer ends of the flat spring 43 and thus lock the housing 5 to the 95 base plate. In removing the housing from the base plate the outer ends of the flat spring 43 are grasped and moved inwardly to release the pins 46 and 47 and thus permit the removal of the housing. If desired 100 a condenser chamber may be provided in the base plate 4 at 52 and a cover plate 53 employed to hold the condenser in place.

Having thus described my invention, what I claim as new and desire to secure by Letters Patent of the United States is:

1. Ignition mechanism for internal combustion engines, comprising a base, a lever pivoted thereto, a pair of coöperating contacts one of which is carried by the lever and the other by the base, a rotatable cam for oscillating the lever, and a spring pressed plunger carried by the lever and forming the cam engaging portion thereof, said plunger being arranged to move relatively to the lever upon rotation of the cam in a backward direction and thus prevent oscillation of the said lever.

2. Ignition mechanism for internal combustion engines, comprising a base, a lever 105 pivoted thereto, a pair of coöperating contacts one of which is carried by the lever and the other by the base, a rotatable cam for oscillating the lever, a plunger carried by the lever and forming the cam engaging 110 portion thereof, and a spring tending to move the plunger in a direction away from the lever pivot, said plunger being arranged to move relatively to the lever upon rotation of the cam in a backward direction and thus 115 prevent oscillation of the said lever.

In witness whereof, I hereunto subscribe my name this 12 day of July, A. D. 1917.

GEORGE F. PALDANI.
